UNITED STATES PATENT OFFICE

151,376

DESIGN FOR A CIGARETTE DISPENSER

Charles Kutik, Paterson, N. J.

Application July 1, 1947, Serial No. 140,039

Term of patent 7 years

(Cl. D85—2)

To all whom it may concern:

Be it known that I, Charles Kutik, a citizen of the United States, residing at Paterson, in the county of Passaic and the State of New Jersey, have invented a new, original, and ornamental Design for a Cigarette Dispenser, of which the following is a specification, reference being had to the accompanying drawing, forming part thereof.

The figure is a perspective view of a cigarette dispenser, showing my new design.

The side of the cigarette dispenser not shown is substantially similar in appearance to the side illustrated, with the exception that the dispensing slots and receivers are omitted.

I claim:

The ornamental design for a cigarette dispenser, as shown and described.

CHARLES KUTIK.
